UNITED STATES PATENT OFFICE.

ABRAHAM J. LOBAR, OF NEW YORK, N. Y.

COMBINED SUSPENDER AND BRACE.

1,317,928.

Specification of Letters Patent.

Patented Oct. 7, 1919.

Application filed October 30, 1918. Serial No. 260,414.

To all whom it may concern:

Be it known that I, ABRAHAM J. LOBAR, a citizen of the United States, residing at 817 Faile St., borough of Bronx, in the county 5 of Bronx and State of New York, have invented certain new and useful Improvements in Combined Suspenders and Braces, of which the following is a specification.

My invention relates to a combined suspender and brace, which is designed to serve 10 as a suspender in an efficient and comfortable manner, and at the same time will also serve as a brace, and assist in causing and maintaining an erect carriage of the wearer. 15 This device can be employed for all the purposes for which suspenders are now used, and at the same time tends to keep the shoulders of the wearer back, straighten his figure, and act as a brace. 20 For many years suspenders have been objected to both on the grounds of comfort and health, because they caused a dragging sensation at the shoulders, especially if they slipped a little, and tended to make the 25 wearer round shouldered. To obviate these defects many devices and improvements have been suggested but without complete satisfaction. As a result belts have come into extensive use in recent years, but they do not 30 impart the trim appearance which a well-dressed man desires, and they cannot be used at all in certain kinds of dress, such as evening dress. In recent years braces something 35 on the style of corsets have also become extensively used, and they have been recognized as valuable in assisting the wearer to maintain a correct posture.

According to my invention a very simple device is provided which obviates the objections 40 now present in suspenders and also acts as a brace. Other objects of my invention are set forth in the following description and drawings which illustrate a preferred embodiment thereof:

45 Figure 1 is a perspective view of the device.

Fig. 2 is a detail side view showing how it is applied to trousers or the like.

Fig. 3 is a section along the line 3—3 of 50 Fig. 1.

The device comprises two loops 3—4 of elastic webbing, connected at their rear by two strips of elastic webbing 1 and 2. When 55 in use, the wearer thrusts his arms through the loops 3—4 so that the tops of the loops shown in Fig. 1 rest comfortably upon his

shoulders near the collar bone, and the strip 1 is at about the level of the shoulders, being preferably a little below this level, and substantially at the level of the arm-pits, 60 while the strip 2 is at about the level of the center of the backbone of the wearer. Metal loops 5 are connected to the webs 3—4, and a connecting tab 6 provided with a snap button 7 of the ordinary type is secured to each 65 of these metal loops 5. The metal loops 5 slide freely with respect to the webs 3—4, so that these always tend to assume the lowermost position when a pull is exerted upon them. 70

The metal rings 8 are connected to the webs 3—4 by means of the metal loops 5, and the connecting means 6. These metal rings 8 are made as small as possible, but are large enough to permit of the easy insertion and 75 withdrawal of the connecting means 6. Tabs 9, 10 and 11, having button-holes 12 are secured to the metal rings 8 by the metal members shown at their inner ends. The metal connecting member between the metal ring 8 and the tab 9 is preferably immovably secured to the metal ring 8, so that this will be directly underneath the connecting means 6, when the device is in operative position, while the metal connecting means between 80 the tabs 10 and 11 and the metal rings 8, can slide freely thereon, being of the nature of closed ears. The tabs 9, 10 and 11 are preferably of non-elastic material and can be 85 freely adjusted with respect to the metal ears 90 at their inner ends by means of the well-known adjusting buckles 16, which require no further illustration, as they have been known in themselves for many years. In this manner the adjustment of the length 95 takes place solely by the adjustment of the lengths of the tabs 9, 10 and 11 while the length of the webs 3—4 remain unaltered.

In use, and as shown in the drawings the tab 9 is buttoned substantially in line with 100 the side seam 15 of the leg 14 of the trousers of the wearer, so as to be directly underneath the center of the arm pit. The tabs 10 and 11 are respectively buttoned in front and in the rear of the tab 9, so as to properly 105 support the front and rear portions of the trousers.

The device is made in various sizes corresponding to the size of the wearer and the lengths of the strips 1 and 2 are such that 110 they exert a gentle but appreciable pull at the back of the wearer and tend to straighten

his shoulders. At the same time the webs 3 and 4 similarly exert a pull to a regulated extent and tend to cause the wearer to assume a correct posture.

5 This is assisted by the fact that the adjustment of the three tabs 9, 10 and 11 can be made to also exert a slight back pull, at the waistline.

10 I have shown a preferred embodiment of my invention but it is clear that numerous changes could be made in its details without departing from its spirit. For instance, the tabs, 9, 10 and 11 could have their bodies made of round cord, instead of flat 15 strips. The metal parts could be replaced by similar parts of any other suitable material, and similarly numerous other changes could be made.

20 I prefer to have the loops of sufficient length to extend from the shoulders to about the level of the floating ribs.

I claim:

25 1. In a trouser support, the combination of two endless loops of webbing connected to each other and adapted to have the arms of the wearer inserted through them, and trouser supporting means connected to the bottoms of said loops, the said trouser supporting means comprising metal rings secured to the bottoms of the said loops, each 30 said metal ring having three tabs connected thereto, the central one of said tabs being adapted to be secured directly underneath the said loop to a button located at the hip 35 portion of the trousers, and the other tabs being adapted to be secured in front and in rear of the first mentioned tab, the outer tabs being secured to said metal rings by intermediate members which are movable with 40 respect to said metal rings, so that said outer tabs and said intermediate members can be held at varying angles to the said central tab.

45 2. In combination, two loops of elastic webbing adapted to have the arms of the

wearer inserted through them, an elastic strip connecting the rears of the said loops at substantially the height of the shoulders of the wearer, a second elastic strip connecting the rears of the said loops at about 50 the middle of the back of the wearer, and trouser supporting means connected to the bottoms of the said loops, the said trouser supporting means comprising metal rings connected to the bottoms of the said loops, 55 each said metal ring having three tabs connected thereto, the central tab being secured to a fixed point of the said metal ring, and the other tabs being movably secured with respect to the said metal ring by means of 60 connecting metal ears, the lengths of the said tabs being adjustable.

3. In combination, two substantially parallel vertical loops made of elastic webbing, an elastic strip under tension connecting the 65 rears of the said loops at about the level of the shoulders of the wearer, a second elastic strip under tension connecting the said rears of the said elastic loops at about the middle of the back of the wearer, metal loops 70 slidably secured to the said vertical loops and located at the bottoms thereof, metal rings removably secured to the said metal loops, trouser supporting tabs secured to the said metal rings, each said metal ring having 75 three tabs secured thereto, the central one of said tabs being immovably secured to the said ring directly underneath the loop, and the other tabs connected to each metal ring being movably secured at each side of the 80 said central tabs by means of sliding metal ears fitted upon the said metal rings, and means for adjusting the lengths of the said metal tabs, whereby the trousers can be supported along the central lines of the legs 85 thereof, and at points in the front and in the rear of the said central lines.

In testimony whereof I hereunto affix my signature.

ABRAHAM J. LOBAR.
